UNITED STATES PATENT OFFICE.

ALVA SMITH WARREN, OF BATAVIA, NEW YORK.

PROPELLER.

1,296,242.

Specification of Letters Patent.

Patented Mar. 4, 1919.

Application filed May 16, 1918. Serial No. 234,982.

To all whom it may concern:

Be it known that I, ALVA S. WARREN, a citizen of the United States, residing at Batavia, in the county of Genesee and State of New York, have invented certain new and useful Improvements in Propellers; and I do declare the following to be a full, clear, and exact description of the invention, such as will enable others skilled in the art to which it appertains to make and use the same.

My invention relates to improvements in propellers used for driving boats or employed for operating other machinery, in which case the propeller is driven by water power.

One object of the invention is to provide a propeller of the endless chain type which may be easily and inexpensively manufactured and installed, yet one which will be highly efficient and durable.

Another object is to provide a novel frame structure including parallel front and rear side bars which carry part of the chain guiding means and at the same time coact with retaining bars in securing the entire device against longitudinal shifting.

Yet another object is to provide a pair of ledges for supporting the entire structure in a water passage, and to make provision whereby these ledges constitute tracks coacting with other tracks carried by the frame to retain the paddles of the endless chain structure in operative position while moving in one direction.

A still further object is to improve upon the construction of the paddles, and their mounting and guiding means.

With the foregoing objects in view, the invention resides in the novel features of construction and unique combinations of parts to be hereinafter described and claimed, the descriptive matter being supplemented by the accompanying drawings which form a part of this specification and in which:

Figure 1 is a side elevation of the propeller installed upon a boat;

Fig. 2 is a longitudinal section of the machine arranged as shown in Fig. 1;

Figs. 3 and 4 are respectively horizontal and transverse sections on the planes indicated by the lines 3—3 and 4—4 of Fig. 2;

Fig. 5 is a detail perspective view of a portion of one of the paddles;

Fig. 6 is a plan view of a portion of one paddle and the adjacent chain;

Fig. 7 is a detail section on the plane of the line 7—7 of Fig. 6.

Fig. 8 is a perspective view of the frame structure;

Fig. 9 is a perspective illustrating the manner in which the propeller may be installed at a water fall or the like to be operated by the water power; and

Fig. 10 is a sectional view of the sluice shown in Fig. 9, illustrating the propeller in side elevation.

In the drawings above briefly described, the letter F indicates the frame of the machine, C has reference to the endless chain structure, L refers to a pair of ledges upon which the frame F is supported, and P designates a water passage in which the ledges L are secured and within which the entire machine is mounted. The passage P may be in the form of a well at the rear end of a tunnel T formed in the bottom of a boat B, in which case the chain structure C will be driven by power to propel the boat, or said passage may form part of a sluice or the like S as depicted in Figs. 9 and 10. When a sluice is used, it is suitably arranged in respect to a waterfall or the like W, so that water will be directed through the sluice to operate the machine by power, whereby it may be utilized for driving other machinery. This arrangement is shown in Figs. 9 and 10, and as seen in Fig. 9, a drive shaft D may extend from the propeller for carrying power therefrom, said shaft being driven from said propeller by means of beveled gears G or other suitable means. When the propeller is employed in connection with a sluice or the like, a gate valve V is preferably employed to control the supply of water thereto.

Having briefly described certain features and the uses of the invention, its novel construction will now be entered into. To this end the numerals 1 designate a pair of parallel longitudinal side beams each preferably formed of upper and lower parallel bars 2 secured between their ends to the opposite sides of blocks 3. Bearing blocks 4 are secured between the bars 2 at one end thereof, other bearing blocks 5 are slidable between the other ends of said bars, and screws or the like 6 are provided for adjusting the blocks 5 longitudinally of the beams 1, said screws being shown threaded through additional blocks 7 secured between the ends of the bars 2 remote from the bearing blocks 4. By

means of suitable roller bearings or the like 8, a pair of transverse shafts 9 have their ends rotatably mounted in the blocks 4 and 5, said shafts carrying sprocket wheels 10 around which the endless chain structure C is trained, said structure including a pair of side chains 11 of any preferred construction. A plurality of transverse shafts 12 extend between the side chains 11 and have 10 their ends rotatably supported thereby, said shafts being provided near their ends with cross arms 13 and at points spaced outwardly from said cross arms, with cross heads 14, said heads having hubs 15 spacing them from the arms 13 and contacting with the latter. Shoes or rollers 16 are located between the cross heads and cross arms, and paddles 17 are clamped between said cross arms on opposite sides of the shaft 12, being 15 preferably connected by transverse straps 18. The several parts are held in operative relation by means of nuts 19 or other suitable heads threaded on the ends of the shafts 12 and bearing against the outer sides of the cross heads 14, these details being best illustrated in Figs. 6 and 7.

Extending across the outer sides of the side beams 1 and secured between their ends to the blocks 3, are front and rear parallel 30 side bars 20 disposed at right angles to said beams 1 and preferably braced together as seen at 21. The lower ends of the side bars 20 carry upper tracks 22 beneath which the shoes 16 travel to retain the paddles 17 in 35 operative position as they move in one direction, the ends of said tracks being turned upwardly at 23 and provided with rollers or the like 24 which guide the paddles onto and from the tracks. By reference more particularly to Figs. 4 and 8, it will be seen that the bars 20 extend a slight distance below the tracks 22 and that they rest upon the ledges L. By this arrangement, the tracks and ledges are spaced apart sufficiently to permit 40 the shoes 16 to travel therebetween, so that these parts form in effect a double track for the shoes:

To insure that the paddles shall not offer resistance on their return travel, a central longitudinal track 25 is provided to position and retain said paddles longitudinally of the upper reach of the chain structure C. The ends of track 25 are turned downwardly at 26 to guide the paddles onto and from said 50 track as seen most clearly in Fig. 2. To support the track 25, transverse bars 27 extend between and are secured to the upper portions of the side bars 20, said transverse bars preferably having arched centers as 55 seen in Fig. 4. To carry the greater part of the weight and thus prevent the paddles from creating a great amount of friction upon the track 25, rollers 28 are preferably provided, the side chains 11 passing over 60 said rollers as seen in Fig. 4. The rollers in 65

question are carried by longitudinal bars 29 whose ends are secured to the side bars 20.

In addition to performing the functions above described, the side bars 20 abut the inner sides of parallel retaining bars 30 70 which are secured in the passage P, whereby to hold the entire machine against longitudinal shifting and at the same time to permit easy removal thereof whenever required. The bars 20 and 30 may be bolted together if 75 desired but in most cases this is not necessary and since it renders the propeller rather hard to remove, this arrangement is preferably not used. By forming openings 31 in the upper ends of the side bars 20, grapples 80 or the like may be easily engaged therewith to hoist the entire propeller out of the passage P whenever required, during which operation the upper tracks 22 move away from the lower tracks or ledges L as will be obvious. 85

From the foregoing, taken in connection with the accompanying drawings, it will be obvious that although I have provided a propeller which is comparatively simple and 90 inexpensive, it will be highly efficient and durable, whether used for driving boats, or itself driven by water power to propel other machinery. Since probably the best results are obtained from the details shown and 95 described, they are by preference followed, but within the scope of the invention as claimed, considerable latitude is allowed for making such minor changes as occasion may dictate. 100

I claim:

1. A propeller comprising an endless chain structure including pivoted paddles, wheels around which said chain structure is trained, a pair of parallel side beams upon whose ends said wheels are mounted, front and rear side bars extending across and secured between their ends to said side beams, longitudinal guide tracks carried by one end of said bars for retaining the paddles in operative position as they travel in one direction along said tracks, transverse bars extending between the other ends of said side bars, and an additional longitudinal track secured to said transverse bars 115 for holding the paddles in inoperative position as they travel on their return path.

2. A propeller comprising an endless chain structure including pivoted paddles, wheels around which said chain structure is 120 trained, a pair of parallel side beams upon whose ends said wheels are mounted, front and rear side bars extending across and secured between their ends to said side beams, longitudinal guide tracks carried by one end of said bars for retaining the paddles in operative position as they travel in one direction along said tracks, and additional chain and paddle-guiding means carried by the other ends of said side bars. 130

3. A propeller comprising an endless chain structure including pivoted paddles, wheels around which said chain structure is trained, a pair of parallel side beams upon 5 whose ends said wheels are mounted, front and rear side bars extending across and secured between their ends to said side beams, longitudinal guide tracks carried by one end of said bars for retaining the paddles in operative 10 position as they travel in one direction along said tracks, and additional chain and paddle guiding means carried by the other ends of said side bars; together with a water passage in which the propeller is 15 located, and parallel retaining bars secured in said passage and abutting said side bars to hold the device against longitudinal shifting.

4. A propeller comprising an endless chain structure including paddles, a frame 20 on which said chain structure is mounted, said frame having transverse retaining bars at its sides, a water passage in which said frame is located, ledges in said passage on which said frame rests, said ledges serving 25 as guiding means for said chain structure, and additional retaining bars secured in said passage and contacting with said first named bars to prevent longitudinal shifting 30 of said frame.

5. In a propeller, a water passage, a frame positioned removably therein, an endless chain structure mounted on said frame and including pivoted paddles having shoes at 35 their ends, and upper and lower tracks receiving said shoes therebetween to hold the paddles in operative position while traveling in one direction, the lower tracks being secured in said passage and the upper tracks 40 being carried by and removable with said frame.

6. In a propeller, a pair of parallel longitudinal side beams carrying wheels at their ends, an endless chain structure trained around said wheels and including pivoted 45 paddles having shoes at their ends, front and rear side bars extending across and secured between their ends to said side beams, tracks carried by one end of said side bars, chain guiding means carried by the other 50 ends thereof, a water passage in which the propeller is disposed, other tracks secured in said passage and parallel with the first named tracks, the two sets of tracks receiving said shoes therebetween to hold said 55 paddles in operative position as they travel in one direction, and retaining bars secured in said passage and abutting said side bars to hold the propeller against longitudinal shifting. 60

7. In a propeller, guide wheels, a pair of endless chains trained around the same, transverse shafts extending between said chains and mounted rotatably on the latter, cross arms of said shafts near the ends thereof, paddles between said cross arms on opposite sides of said shafts, cross heads spaced outwardly from said cross arms and having hubs mounted on said shafts and abutting said cross arms, heads on said shafts abutting the outer sides of said cross heads to retain all parts in place, rollers mounted between said cross arms and cross heads, and tracks which said rollers engage to retain the blades in operative position as they 70 travel in one direction. 75

In testimony whereof I have hereunto set my hand.
